UNITED STATES PATENT OFFICE.

G. HENRY HULSKAMP, OF TROY, NEW YORK.

PIANO-FORTE ACTION.

Specification forming part of Letters Patent No. 36,712, dated October 21, 1862.

To all whom it may concern:

Be it known that I, G. HENRY HULSKAMP, of the city of Troy, in the county of Rensselaer and the State of New York, have invented a new and useful Improvement in the Actions of Piano-Fortes; and I do hereby declare that the following is a full and exact description thereof, reference being had to the annexed drawings, and the letters of reference marked thereon.

My improvement is represented by the drawing, which is a vertical section through the middle of one of the keys A A. It represents the several parts in their full size and proper proportions. The red-shaded parts are those that are covered with cloth or buckskin to prevent noise. The blue-shaded parts are screws, metallic wires, &c.

A bar, B, extending lengthwise across the piano-forte, is firmly attached to the frame in the usual manner. To this bar is screwed the hinge-butt C, and to the latter is attached the hammer-butt D, with the hammer E by the joint 1. Upon the keys A A, I attach a lever, F, by the screws G and H, and to this lever is attached the jack or hammer-lifter J by the joint 2. To the jack or hammer-lifter is attached, by the joint 3, a detacher. (Represented at J.) This is pressed upward by a spring, N, inserted into the lever F, and bearing against a projection on the detacher until the upward motion of the detacher is arrested by a stop, K, attached to the projection on J. By a screw the length of K may be readily adjusted. To the detacher J is also attached a stem or screw, L, upon which a round-headed polished nut is screwed. Its height can be adjusted by its screw, in order to bear against the point M of the hammer-butt D, for the object hereinafter stated. The wire spring N also serves to press the hammer-lifter or jack against the hammer-butt D.

O is the back check, to prevent the rebound of the hammer, in the usual form. A wire spring, P, attached to the hinge-butt C, pressing against a piece of felt, Y, glued onto the side of the hammer-butt, serves to support and to regulate the weight of the hammer. A little cut is made in the felt, to receive the spring. The points M and X of the hammer-butt are at the same distance from the center 1, and should be made to press equally on the ending

of the jack and the end of the nut on L; but when the hammer is raised by pressing on the key as the point M moves somewhat backward toward the jack as well as upward and the nut moves forward and upward, they become disconnected by a small space, so that the point M has a free-motion toward the jack, without touching the same, when the hammer is raised.

Q represents one of the strings.

The operation is as follows: When the back part of the key is raised by pressing down the front of it, the hammer will be carried rigidly upward by the jack pressing against the hammer-butt until it has been brought to within three-eighths of an inch from the strings. Then the end of the detacher J strikes against the bar B, pushes the jack out from under X, and becomes fully detached when the hammer has been brought to within about one-eighth of an inch from the strings. After the blow has been given the hammer will descend about one-half of an inch. The point M will then fall upon the nut on L, the hammer will become connected with the head of the back check, which prevents the rebound of the hammer. As the key descends, the spring N presses the detacher J and its stem L upward under the hammer-butt at M, by which the hammer is slightly raised. The jack will connect again with the hammer-butt, so that the blow may be repeated with a small part only of the motion of the key. The friction by detaching the jack from the hammer-butt has been a great defect in the actions at present in use. By my construction when the key is pressed down the hammer rises to about three-eighths of an inch from the strings. Then the detacher J strikes against the bar B without friction, and the jack becomes detached with a very quick motion, and this adds to the power of the blow. It is thus seen that the stiffness common in other actions by detaching the jack is also here obviated by the elastic detacher J, and this adds much to the lightness, power, and durability of the action.

It is important in piano-forte actions to produce by the normal and only small movement of the keys the greatest power to the blow of the hammer, combined with an easy, light, and elastic touch.

To regulate the height of the jack, a screw,

H, under the end of the lever F, is inserted in the key, and its rounded head extends up into a hole in the lever, through which it is regulated. An upright piece of wood, S, glued onto the lever F, serves for the other bearing of the lever on the key. Another screw, G, let down about half-way into the lever, holds it to the key. Much difficulty has heretofore been experienced by this lever getting loose and rattling from the effects of heat and the shrinking and swelling of the wood, and the object of this mode of attaching is to remedy that difficulty. Another mode of attaching it is represented at U and V, and it is apparent that any shrinking or swelling of the wood will be compensated and any looseness prevented. The upright piece of wood W in the hinge-butt is for the same purpose as the piece S in the lever F. A spiral spring, T, attached to the jack I and the detacher J, as shown in the

drawing, will be found more convenient in actions for small pianos than the spring X, attached to the lever F.

What I claim as my invention, and desire to secure by Letters Patent, is—

1. The combination of the vibrating detacher J and its adjustable stem I, with the jack I, substantially as herein shown and described.
2. The form and peculiar construction of the hammer-butt D, of the jack I, and of the detacher J, substantially as described.
3. The mode of attaching the levers, hinge-butts, &c., substantially as described, or its equivalent, for the purpose of preventing looseness and the effects of shrinking and swelling.

G. HENRY HULSKAMP.
